MONOLITHIC STRUCTURE

Eugene B. White, Oak Park, Ill.

Application October 29, 1937, Serial No. 171,728

13 Claims. (Cl. 72—66)

My invention is concerned with a fireproof, monolithic building construction, and is designed to produce a novel structure, preferably formed by my novel method, which structure shall embody a minimum of concrete or similar plastic material, with a minimum of reenforcing material and at a minimum expense, and in the preferred form without the necessity of employing form-work or shoring.

To this end, in the preferred form, I employ for the beam members of a floor, roof, or similar structure, channels formed of sheet metal and adapted to be fabricated to the desired lengths in the shop, and preferably having a reinforcing rod or rods secured therein at that time. These beam members as so far described are of themselves of sufficient strength to support the workmen in placing them, and the floor slabs which they support and which are finally connected thereto as described.

For the body of the flooring or roofing I preferably employ thin, precast slabs of concrete or some similar plastic material which has reenforcing material, preferably composed of sheets of expanded metal or welded steel wire mesh extending throughout the length thereof and projecting from their ends, for the purpose herein-after described. These are secured on or to the beams by placing the expanded metal or other reinforcing material projecting from the ends of the slabs in the hollow of the channels, and pouring concrete or some similar material into the channels, thereby binding the slabs to the concrete beams, which are further reinforced by the expanded metal of the slabs in addition to the reinforcing rods primarily employed for that purpose.

While the sheet metal channels covering them furnish some additional reenforcement, their primary function is that of forming the molds for the beams, since the reinforced beams when hardened are strong enough to carry any load to which they may be subjected without the help of the channels which might become useless as a reinforcement in the event of a fire which should reach and distort them.

To illustrate my invention I annex hereto two sheets of drawings, in which the same reference characters are used to designate the identical parts in all the figures of which:

Fig. 1 is a perspective view of a portion of a floor structure employing my invention and with various portions thereof broken away;

Fig. 2 is a plan view on a larger scale of a portion of a floor employing my invention;

Fig. 3 is a view in section on the line 3—3 of Fig. 2;

Figs. 4, 5 and 6 are views similar to Figs. 1, 2 and 3 but showing a modified construction in which the metal channels are dispensed with;

Fig. 7 is an enlarged detail in perspective showing how the reenforcing material of the slabs may be connected to the reenforcing material of the beams; and

Fig. 8 is a detail in vertical section showing a modified structure for the same purpose as that shown in Fig. 7.

As heretofore constructed reenforced concrete buildings, and especially the floors thereof, have usually been composed of comparatively thin sheets or slabs of reenforced concrete strengthened by employing reenforced concrete beams beneath the slabs and integral therewith, and of such size and so located as might be necessary to give the desired strength for the particular load the floor is expected to sustain.

To make these, removable forms and form work supported by shoring had to be employed, all of which had to be removed after the concrete had set, all of which involved extra expense and delay.

In carrying out my invention in its preferred manner, in place of the forms for the beams above referred to, I employ channels 10 of sheet metal, possibly as thin as $\frac{1}{16}$ of an inch, and of the shape shown and with the inwardly projecting flanges 10^a at their open sides. These are supported at their ends upon the foundations 21, and upon intermediate girders 20, if the size of the building is such as to require their use. They will contain the longitudinal reenforcing rods 15, preferably welded in place at the factory in the proper position and supported by saddles 22, likewise secured in place in the beams.

I preferably form the floor proper by slab members 11, preferably pre-cast at the factory and made of any desired plastic material properly reenforced, as by strips of expanded metal 12, the ends of which must project from the ends of the slabs 11, so that the projecting ends can be bent down into the channels as seen in Figs. 1 and 3. I use floor slabs 11 of such a length that, as seen in Figs. 1 and 3, their ends just reach over the flanges 10^a of alternate channels 10, and at the center so that it will register with the intermediate channel which it crosses, I form the dowel hole 13. Into the space between the ends of the slabs I pour a thin plastic cementitious material 26, which fills the interior of the channels 10 and the space between the ends of

the slabs to produce an unbroken floor surface. The cementitious material will flow the length of the channels 10 and when they are completely filled, it will rise through the dowel holes 13, showing that the pouring is completed, and when it hardens, it assists in holding the slabs 11 in place, which, however, is effected mainly by the cementitious material hardening in the expanded metal ends 12, thereby forming a reenforced concrete system. In this manner a very strong, yet light structure is obtained with only a fraction of the material heretofore considered essential for such structures. The channels 10 being strong enough to support the men placing the slabs 11 and pouring the cementitious material 26, no form work or shores are required.

I obtain the necessary strength by forming the hollow metal beam section 10 of the design shown in Fig. 3, and I have found it would be necessary for this sheet steel section to have a "moment of inertia" of at least 4.96 inches to the 4th power about the neutral axis of the section. Moment of inertia of the section about the neutral axis 23 as here used is the name for a certain constant depending on the shape of the sheet steel cross-section. In practice I have found it to be desirable that sheet steel of the thickness of at least 16 gauge U. S. Standard, to be used as before stated.

30 In the construction of modern buildings the floor spans encountered vary from three to twenty-four feet, with floor loads varying from 50 pounds per square foot up to 500 pounds. In order to enable this invention to be used commercially, the size of the sheet steel sections used in forming the supporting beams, should be such as to give the reenforced concrete beams enclosed thereby the required strength necessary to carry construction loads in a floor structure without the assistance of the steel channels. In practice I have found that the spacing indicated in Figs. 2 and 3 between adjacent sheet steel sections 10 may vary considerably, depending upon the depth and gauge of said sections.

45 As illustrative of the unusual load-carrying capacity of a reenforced light-weight concrete floor, embodying the present invention, and of its remarkable strength compared to its own weight, the following data is furnished for a commercial form of the present reenforced light-weight concrete system in which the sheet steel sections 10 are shaped as illustrated in Fig. 3 and are spaced apart 36 inches on center and covered with interlocking pre-cast slabs which are connected together to form a floor panel. The sheet steel sections are 4½ inches by 6 inches as shown, and the pre-cast light-weight concrete slabs are two inches thick with extended expanded metal reenforcing 12, serving as the web and shear concrete beam reenforcing and means of connection. The weight in pounds per square foot of the entire panel, including beams and floor, is 21 pounds, capable of carrying a safe live load of 80 pounds per square foot, with a span of 16 feet.

60 65 The foregoing description of the structure shown in Figs. 1, 2 and 3 and the generic claims directed thereto may be considered as a division or continuation of my application Serial No. 102,669, filed September 26, 1936, and in Figs. 4 to 7, I have shown a modified structure erected by a somewhat modified method.

The slabs 11 are constructed just the same and are provided with the central dowel holes 13 for the same purpose, but I have shown reenforcing material 12^a as consisting of welded steel wire

mesh with its projecting ends turned down and extending into the channels 10^b, which in this form consist of the board forms heretofore commonly used and supported upon the foundations 21 and upon intermediate girders 20, and immediately upon the removable shoring 10^c, their relation to the girder and foundations being such that these forms 10^b can be removed when the concrete is hardened. The channels 10^b will contain the reenforcing rods 15 as before and the dimensions of the beams and reenforcing rods will be such that the beams will support the desired load when the concrete has hardened and the boards 10^b are removed.

To increase the monolithic effect, before the 15 cementitious material 26 is poured, I place in the dowel holes 13, the metal loops or stirrups 36, which connect the reenforcing material 12 or 12^a with the rods 15, and these loops may be of any desired shape or arrangement for this purpose, as for example that shown in Figs. 6 and 7, where the bottoms of the loops hang over a welded juncture of the steel wire mesh and their ends extend down into the plane of the rods 15, or, as shown in Fig. 8, in which the bottom of 20 the loop 36 rests on or is beneath the rod 15 and its ends are turned over to engage the reenforcing material 12 or the sides of the dowel hole 13.

25 It will be obvious that the fundamental method of erecting the structure in this modified form 30 is the same as where the metal channel is employed, except for the added step of removing the wooden channel and its supports.

While I have shown and described my novel structure as embodied in the form which I at present consider best adapted to carry out its purposes, and as erected by the best method, it will be understood that it is capable of modifications, and that I do not desire to be limited in the interpretation of the following claims, except 35 as may be necessitated by the state of the prior art.

40 What I claim as new and desire to secure by Letters Patent of the United States is:

45 1. In a monolithic cementitious structure, the combination with parallel beams of thin sheet metal having a channel shape in cross section, of slabs of hardened plastic material with the ends of the slabs in alignment separated where they rest on the beams, reenforcing material for the slabs extending throughout their length and having its ends extending into the beams where their ends are separated, hardened plastic material filling the beams and spaces between the ends of the slabs, the slabs extending across an intermediate channel and alternating so that adjacent slabs have their ends resting on different beams, said slabs extending over the intermediate beams having dowel apertures filled by the hardened plastic material registered with said intermediate beams, and reenforcing members extending through the dowel holes down into the hollow of the beam.

in the bottom of the channel, and cementitious material filling said channel and extending up through and filling said dowel holes in the slab substantially as and for the purpose described.

5. 3. In a fireproof monolithic structure, the combination with a parallel series of thin metallic channels having flanges on their open sides and reinforcing rods extending throughout their entire length close to but away from their bottoms, 10 of supports for the ends of the channels, reenforced slabs of cementitious material extending between non-adjacent channels and having their ends resting on said flanges and the reinforcing material projecting from the ends and extending 15 down into the channels and with dowel holes therein registering with the open sides of the channels they cross, and cementitious material filling the channels and dowel holes and surrounding the reinforcing rods and the reinforcing material extended thereinto to form a monolithic T-beam structure.

4. A fireproof monolithic structure as described in claim 3 in which there are stirrups in the dowel holes engaging the reinforcing material of the 20 slabs and extending to the reinforcing rods for the purpose described.

5. In a monolithic cementitious structure, the combination with a series of cementitious beams having their upper portions narrowed by the formation of offsets in each side thereof and provided with integral reinforcing material extending the entire length thereof and completely imbedded therein, of slabs extending across some of the beams and having dowel holes therein registering with the beams they cross and their ends resting on the offsets of other beams, the dowel holes of the slabs being filled by the cementitious material of the beams they cross.

6. A monolithic cementitious structure as described in claim 5 in which reinforcing material extends through the dowel holes and is imbedded in the cementitious material.

7. In a monolithic cementitious structure, the combination with a thin metallic channel having flanges at its open side, of slabs extending across said channel and having dowel holes registering with the opening of the channel, cementitious material filling said channel and extending up through and filling said dowel holes in the slabs, 50 and stirrups placed in said dowel holes and engaging the reinforcing material of the slabs and extending close to the bottom of the channels.

8. In a building construction, the combination with parallel horizontal beams of thin sheet metal having a channel shape in cross section with their open sides uppermost, of slabs of hardened plastic material resting thereon, with the ends of the slabs in alignment separated where they rest on

the beams, reinforcing material for the slabs extending throughout their length and having its ends extending into the beams where their ends are separated, and hardened plastic material filling the beams and spaces between the ends of the slabs, the slabs extending across an intermediate channel and alternating so that adjacent slabs have their ends resting on different beams, and having dowel holes in the slabs extending over the intermediate channels registered therewith and filled with the hardened plastic material.

9. In a building construction, the combination with parallel horizontal beams of thin sheet metal having a channel shape in cross section with their open sides uppermost, of slabs of hardened plastic material resting thereon, with the ends of the slabs in alignment separated where they rest on the beams, reinforcing material for the slabs extending throughout their length and having its ends extending into the beams where their ends are separated, hardened plastic material filling the beams and spaces between the ends of the slabs, the slabs extending across an intermediate channel and alternating so that adjacent slabs have their ends resting on different beams, and having dowel holes in the slabs extending over the intermediate channels registered therewith and filled with the hardened plastic material, and reinforcing members which extend through the dowel holes down into the hollow of the beam.

10. In a monolithic cementitious structure, the combination with a series of cementitious beams suitably reinforced throughout their entire length, of precast cementitious slabs suitably reinforced throughout their entire length with the reinforcements at their ends extending into the beams on which said ends rest, some of the slabs spanning and crossing the beams between their ends, and having dowel holes therein registering with said beams, the cementitious material of said beams extending up through said dowel holes as and for the purpose described.

11. A monolithic cementitious structure as described in claim 10 in which there is reinforcing material extending up through said dowel holes.

12. A monolithic cementitious structure as described in claim 10 in which there is reinforcing material extending up through said dowel holes and connecting the reinforcing material of the beams with that of the slabs.

13. A monolithic cementitious structure as described in claim 10 in which reinforcing stirrups extend up through said holes.

EUGENE B. WHITE.
